CLOSURE FOR NONREFILLABLE CONTAINERS

Jose Soto del Llano, Habana, Cuba, assignor of
one-fourth to Ricardo Moré Ferrer, Habana,
Cuba

Application March 21, 1942, Serial No. 435,710
In Cuba June 21, 1941

2 Claims. (Cl. 215—23)

This invention relates to non-refillable containers, and particularly to bottles intended for receiving high quality beverages such, as for instance, spirituous liquors.

An object of the invention resides in the provision of a closure which in the normal upright position of the bottle will tend to seal the latter owing to the gravity induced position of a slideable valve.

Another object of the invention is to provide in association with a non-refillable container, a closure wherein a weight appended to a flexible fastening member connected to the slideable valve will cause the valve to slide in a predetermined direction and seal the inlet for air and liquid whenever the container is inclined to inverted position or placed horizontally.

It is in general an object of the invention to prevent the introduction of liquid and also seal the inlet for air on the container whenever the container is placed in a position different from upright position, and at the same time an attempt is made to introduce liquid into the same.

The invention is described in the following specification with reference to the accompanying drawing, in which,

Fig. 1 is an outer elevational view of a bottle neck provided with the closure according to the present invention;

Fig. 2 is a vertical sectional view of the closure and bottle neck of Fig. 1 in normal or upright position;

Fig. 3 is a sectional view similar to that of Fig. 2, showing the bottle of which the neck only is indicated in inclined inverted position;

Fig. 4 is a detail elevation for a casing portion of the closure;

Fig. 5 is a detail elevation of a valve carrying member of the closure;

Fig. 6 is a detail elevation of the valve and a weight connected with the valve as well as a sleeve connected with the valve and adapted to limit the movement of said weight;

Fig. 7 is a sectional view of the assembly of elements illustrated in elevation in Figs. 5 and 6.

The non-refillable closure comprises a casing 1' of cylindrical or square cross-section which is open at its lower end and is reduced in its upper portion as by the provision of a shoulder 30. This casing 1' may be made of metal having a coating of tin on its inner surface, or it may be produced of plastic material which is proof against alcohol. The casing 1' is retained in position upon the mouth of the bottle by a metal strap 5' which hugs the casing very closely

so as to completely surround the same with the exception of the very top portion thereof and also extending below said casing to be fitted to the bottle neck 4'. The opening 8' in the top of the casing 1' may be closed by a cork or other plug 37 and the lower face of the casing is supported on the mouth of the bottle, while an annular packing 3' is interposed between the bottle and the casing.

10 A valve carrying member 12' is disposed within the casing 1' and separated from the inner face of the casing by an annular interspace 39. The lower portion of the valve carrying member 12' fits the interior of the mouth of the bottle neck 4', and this valve carrying member, furthermore, is provided with a flange 31 between the upper portion of the reduced size and the lower portion of a size to fit the interior of the mouth of the bottle. The flange 31 of the valve carrying member also rests on the annular packing interposed between the bottle mouth and the casing 1'. For this purpose, the casing 1' is provided on its lower face with a recess 32 into which the flange 31 is adapted to fit. The upper end 15 of the valve carrying member 12' is closed by a wall 33, and a plurality of openings 18' is provided above the flange 31 of said member.

15 A valve 17' comprising a solid body is slidably mounted in the interior 34 of the valve carrying member 12'. The lower portion of the valve carrying member is provided with internal threads 35 for engagement with the screw threads on a sleeve 36 inserted into the lower portion of the valve carrying member and holding the body of the valve 17' against withdrawal from the interior of said valve carrying member. The sleeve 36 also is provided with an annular series of openings 16' to admit liquid into said sleeve from the interior of the bottle. Upon movement of the valve body 17' away from the position shown in Figs. 2 and 7, this liquid having found access into the interior of the sleeve 36 will then be able to flow through the openings 18' of the valve carrying member 12' into the annular space 38 of the casing to be discharged through the opening 8'. A position in which a path for the liquid through the openings 16' and 18' is freed is indicated in Fig. 3.

20 A screw-threaded stem 21' secured in the body 50 of the valve 17' projects into the sleeve 36, as shown in Figs. 2, 3 and 7, and this stem is in pivotal connection with a link 22', the other end of which link is pivotally connected with the weight 23'. The length of the projecting portion 55 of the stem 21' and of the link 22' and the per-

taining portion of the weight 23' are selected in such manner that in upright position the weight appears beneath the lower opening of the sleeve 36, while upon inversion of the bottle to the position shown in Fig. 3, said weight will be in engagement with the lower edge portion of the sleeve 36. The weight 23' is of double frustoconical shape with its larger section at the center. At this central section of maximum area, the diameter of the weight is greater than that of the opening of the sleeve 36. Owing to this shape of the weight 23', the weight will remain seated on the lower edge of the sleeve 36, in sealing relation thereto when the bottle is inverted, as shown in Fig. 3.

In this position of the bottle, the valve 17' will slide downwardly in the valve carrying member 12 until it engages the wall 33 of said member. In this movement, the sliding valve 17' carries with it the assembly of elements 21', 22' and 23', while freeing the openings 16' and 18'. The atmospheric air may then enter through these openings and thereby facilitate the pouring of the contents from the bottle through other openings of the same series.

If upon placing the bottle in the position shown in Fig. 3, an attempt should be made to inject liquid by pressure through the opening 8' in the casing 1', this liquid having passed under pressure, the openings 18', will act upon the weight 23' to push the same upwardly away from the free edge of the sleeve 36' to move thereby the valve 17' into a position in which it obstructs the openings 18', as shown in Fig. 7. Obviously the same movement of the valve 17' will take place when the bottle has been placed in horizontal position and an attempt is made to inject liquid under pressure through the opening 8' in the casing.

It is understood that the shape of the closure device as well as the nature of the material of which it is made may be varied without altering thereby the essential character of the invention within the scope of the claims appended hereto.

What I claim is:

1. A closure for non-refillable containers, comprising an outer casing adapted to rest on the

container mouth, a metal strap which inviolably secures the casing on the container mouth, a valve-carrying member closed at its top end and opened at its lower end and which is provided

- 5 at its middle portion with an annular flange resting on the container mouth and fitting with the lower edge of the casing thereby providing an annular space between the valve-carrying member and the casing, a sleeve threaded within the lower portion of the valve-carrying member and providing an annular space between the sleeve and the container neck, a series of side openings in the valve-carrying member above the flange, a valve fitted and slidable within the valve-carrying member and adapted to seat on the upper edge of the sleeve, a series of side openings at the projecting portion of the sleeve, and a weight 10 flexibly connected to the valve and adapted to laterally fall beyond the lower end of the sleeve.
- 15 2. A closure for non-refillable containers, comprising an annular packing placed on the container mouth, an outer casing adapted to rest on the packing, a metal strap which inviolably secures the casing on the container mouth, a 20 valve-carrying member closed at its upper end and opened at its lower end and which is provided at its middle portion with an annular flange resting on the packing and fitting with the lower edge of the casing thereby providing an annular 25 space between the valve-carrying member and the casing, a sleeve threaded within the lower portion of the valve-carrying member and providing an annular space between the sleeve and the container neck, a series of side openings in 30 the valve-carrying member adjacent the annular flange and above same, a valve adjusted within the upper portion of the valve-carrying member and providing an air chamber between same and the upper portion of the valve-carrying member 35 40 to run within same and adapted to seat on the upper edge of the sleeve, a series of side openings at the projecting portion of the sleeve, and a weight flexibly connected to the valve and adapted to laterally fall beyond the inner end of 45 the sleeve.

JOSE SOTO DEL LLANO.
